UNITED STATES PATENT OFFICE.

ISAAC W. WEPPLO, OF CHICAGO, ILLINOIS.

PUMP

1,415,617.

Specification of Letters Patent.

Patented May 9, 1922.

Application filed November 15, 1920. Serial No. 424,256.

To all whom it may concern:

Be it known that I, ISAAC W. WEPPLO, a citizen of the United States, and resident of Chicago, in the county of Cook and State 5 of Illinois, have invented new and useful Improvements in Pumps, of which the following is a specification.

This invention has relation to a pump and refers more particularly to means for lubricating such pump.

The object of my invention is the provision of means for effectively lubricating the piston of a pump or other apparatus in which a piston is slideable within a cylinder. A further object is to provide a piston head of novel construction for the purpose of accommodating such lubricating means.

The aforesigned objects and the important 20 features of my invention are hereinafter fully explained and illustrated in the appended drawing of which,

Fig. 1 shows, in side elevation, and partly in section, a pump structure embodying the 25 invention, and

Fig. 2 is an enlarged view of the piston of said structure.

The reference numeral 1 denotes a pump cylinder fitted at the top with a valve mechanism 30 2, which through the medium of an arm 3, a connecting rod 4 and a lever 5 is connected to be operated from the crank 6 of a crank shaft 7. The latter is suitably supported, as by a plurality of bearing stands such as shown at 8, and said stands may be mounted on a base 9. The crank shaft 7 is provided with a second crank 10 shaped to operate in a slot 11^a of the piston rod head 11. The cylinder 1 is rigidly 40 mounted above the base 9 through the medium of a suitable supporting stand 28.

The crank shaft 7 is rotated by any suitable means (not shown), and it is connected to reciprocate a piston 21 within the cylinder 1, through the medium of the said crank 10, which, as stated, rides in the slot 11^a of the piston rod. The valve mechanism comprises a cylindrical stem 12 having an L-shaped passage 12^a for registration 50 with an inlet port 14 and an outlet port 13. Rigid on one end of the valve stem is the arm 3 which, as stated, is operatively connected with the lever 5.

The crank shaft 7 is rotating in a clockwise direction, and it is, in the position

shown in the drawing, pushing the piston upward and discharging the contents of the cylinder through the outlet port 13. The piston is at this time traveling at its maximum speed, and the speed will now gradually decrease. The arm 3, and therethrough the valve stem 12, on the other hand, is now at a stand-still, with the discharge port full open, and it is just at the point beginning its downward movement. When the piston reaches the top of its movement it is found that the outlet port 13 will be closed and that the inlet port is just commencing to open, and it will open very fast. As the piston then commences to descend with increasing speed 65 it is found that the valve stem gradually comes to a stop. And when the piston gradually loses speed toward the end of its down stroke, it is noticed that the valve stem quickly picks up speed, so as to close the inlet port by the time the piston reaches the bottom. In other words, there are two crank movements, controlled by the two cranks 6 and 10, so related that when one is at its highest speed the other is found substantially at rest on or near its dead center. This is necessary in order that one port or the other may be open during the travel of the piston.

Of course, I wish it understood that the 85 structure illustrated in the drawing is not shown mechanically perfect, and that minor mechanical refinements, such as the relative positions of the cranks and the shape of the slots in which the cranks operate, are 90 carried out in the design of the pump actually in use. The drawing only illustrates the principle of my invention. My aim is only to explain that, when one member is most active, then the other member is most 95 nearly inactive, in order to give the pump the maximum time to load and discharge, and so that the completion of the closing of one port and the beginning of the opening of the other may occur quickly while the piston is substantially at rest at either end of its stroke.

Now it is important to note that the piston 21 is made with two heads 29 and 30, and the construction of said heads may be identical, if preferred. Between the said heads is an annular space, due to which a chamber 15 is formed when the piston is in position. A passage 16, or a plurality of such passages, leads from said chamber, through a 110

duct 17^a of the piston rod 17, thence through a tube 18, and terminates within a lubricant receptacle 19. This receptacle, which may be of any standard shape and construction, is positioned well above the cylinder, and this feature is very important for the reason that a great deal of pressure is thereby exerted upon the lubricant confined within chamber 15. The object of maintaining the lubricant within said chamber under pressure is in the first place to insure perfect and sufficient lubrication of the piston head, but also, and this is even more important, to seal the passage from the outer atmosphere to the space above the piston.

My invention is primarily intended for use in establishments making heavy fluids, such as tooth paste. The lubricant used is of a nature analogous to the composition of such paste, as for instance glycerine. The problem is to deliver an exact amount to the paste receptacle, which in this case is a collapsible tube. With a pump of ordinary construction, such as has heretofore been used in such establishments, it has been found that more or less air would find its way into the pump chamber at each stroke, and that therefore the quantity delivered would vary. This again necessitated the delivery of an excess amount and a consequent waste.

The stroke of the piston of my invention is adjustable by suitable means, such as a screw joint 20 in the piston rod, and by thus adjusting the stroke, I am able to deliver an exact amount to each tube. Anyone who has witnessed the enormous waste in a large tooth paste establishment, caused by the overflowing of the tubes in filling, will appreciate the importance of my invention, and the great saving effected.

More specifically the piston comprises the body portion 21 and the integral shank or rod 17, and this rod is provided with screw threads 17^a. A cylindrical stud 21^a extends upward from the body, and this stud is made with screw threads 21^b. The piston head 29 is placed on said stud, whereupon a nut 25 is applied to the screw threads and for the purpose of locking the piston head in position. It is noticed, in Fig. 2, that this nut has not been turned up tight, for the sake of clearness, but the structure is shown fully assembled in Fig. 1. The piston head 30 is put in position from the bottom of the piston rod 17, before the pipe 18 is attached,

and it is then similarly tightened in position by a nut 26.

The piston head 29 comprises a pair of cup shaped rings 22, which are placed back to back and loosely fitted on the stud 21^a. Within each ring, and slidably fitted on the stud, is a grooved disc 23, and within the groove of each disc is placed a spring ring, the function of which is to urge the ring against the sides of the cylinder. The piston head 30 may be of exactly the same construction, the only difference in shape being that the hole in the rings and discs must be large enough to slip over the screw threads 17^b. The cup shaped rings 22 are made of suitable flexible material, such as leather, and the back to back relation of each pair is important, as it insures a tight joint on each side of the piston body 21 both on the up and down stroke. Hence no air can get into the space 15 from the bottom, and no paste can enter from the top, and the space is always full of glycerine.

In the above description I have set forth very clearly the construction and operation of my invention. I wish to state, in conclusion that I may modify this construction to suit operating conditions so long as the salient features as set forth in the annexed claims, are preserved.

I claim:

1. In a measured delivery pump, a reciprocating piston, an oscillating valve, means for operating said piston and valve in the proper time relation, said piston having a central body and a pair of heads, one head attachable from each side of said body, each head comprising a pair of flexible rings and having resilient members urging said rings against the sides of the cylinder, and means for maintaining the space between said heads constantly filled with lubricants.

2. A piston having a cylindrical body and provided with rods extending both ways, one rod connected for imparting reciprocations to the piston, screw threads on both rods in spaced relation to the body, a piston head attached from each end and held clamped against the body by threaded nuts engaging said screw threads, each head comprising a pair of cup shaped rings assembled back to back, grooved discs within each cup for spacing purposes, and resilient members in the grooves of said discs and yieldingly pressing against the inner periphery of said rings.

ISAAC W. WEPPLA.
